UNITED STATES PATENT OFFICE.

EDWARD HAMEL, OF WILCOX, SASKATCHEWAN, CANADA.

OIL-CAN PUMP.

Application filed June 23, 1923. Serial No. 647,269.

To all whom it may concern:

Be it known that I, EDWARD HAMEL, a subject of the King of Great Britain, of the town of Wilcox, in the Province of Saskatchewan, Canada, have invented certain new and useful Improvements in Oil-Can Pumps, of which the following is the specification.

The invention relates to improvements in oil can pumps and an object of the invention is to provide a pump attachment for the can which can be removed as a unit from the oil can or container and which is arranged so that it can be readily operated by thumb pressure.

A further object is to construct a pump which will effectively discharge oil from the can in either the vertical or horizontal position and which is designed such that it will discharge practically all the oil from the can.

A further object is to construct the device in a comparatively cheap and durable manner.

With the above more important objects in view the invention consists essentially in the arrangement and construction of parts hereinafter more particularly described and later pointed out in the appended claims, reference being had to the accompanying drawing in which:—

Fig. 1 is a side view of an oil can provided with my pump.

Fig. 2 is a plan view of the device.

Fig. 3 is an enlarged detailed vertical sectional view centrally through the device.

Fig. 4 is an enlarged detailed vertical sectional view through the check valve.

Fig. 5 is an enlarged detailed horizontal sectional view centrally through the suction valve.

In the drawing like characters of reference indicate corresponding parts in the several figures.

The can or oil container 1 is provided with the customary handle 2 and finger grip 3 at one side and is fitted with the filling plug 4 at the other. The top of the can is provided with a comparatively large opening 5 surrounded by a comparatively large externally screw threaded upstanding flange or collar 6. The opening 5 which is circular has the centre point thereof positioned to the side of the vertical axis of the can body. Internally at the side opposite to the handle the can is provided with a

semi-circular horizontally disposed partition or oil stop 7 which is situated approximately half-way up the side of the can.

The pump utilized for forcibly expelling the oil from the can is shortly described and it is arranged so that it can be attached to the can as a unit, being held in place by a screw threaded cap 8 applied on the flange 6. Within the cap, which it will be observed is provided with an inturned flange, I locate a disc like closure plate 9 adapted to seat on said flange 6 and to be held firmly in place by the flange of the cap when the same is screwed tightly down. A washer 10 is placed between the cap and the collar to prevent any possibility of oil leakage.

The oil delivery spout 11 passes centrally through the plate 9 and is permanently attached thereto. The upper end of the spout tapers as is customary and the lower end thereof opens to the interior of a horizontally disposed oil box 12 permanently secured to the spout. A check valve 13 of any approved type is inserted in the lower end of the spout, the check valve permitting of the flow of oil from the box to the spout but preventing a return flow from the spout to the box. The ends of the box are closed and one end, which is inset, is provided with a centrally positioned valve opening 14 normally closed by a suction valve 15, such latter valve being in the form of a flat strip or plate carrying a pair of guide stems 16 and 17, which pass slidably through the end of the box at opposite sides of the valve opening and are fitted with springs 18 normally acting to hold the said valve closed.

A cylinder 19 is permanently secured to the opposite end of the box, said cylinder having the lower end thereof opening to the interior of the box and the upper end thereof contracted and communicating with a guide tube 20 which passes upwardly through the plate 9 and terminates in any suitable type of stuffing box 21. A plunger or piston 22 provided with the customary washers is slidably mounted within the cylinder and the piston is fitted with an extending piston rod 23 passing slidably upwardly through the tube and stuffing box and terminating in a thumb grip 24 permanently attached thereto. The thumb grip extends radially from the spout and has the inner end thereof notched out as indicated

at 25 to receive the spout and the outer end thereof positioned directly over the handle of the can. In this way the grip is convenient to the thumb when one is holding 5 the can by the handle and the spout forms a guide preventing the rotation of the thumb grip. A coil spring 26 is interposed between the plunger and the bottom of the box 12, this spring acting to normally maintain 10 the plunger in its upper position within the cylinder.

The pump unit is placed in the can by initially tilting it to permit the oil box to enter the can. After one has the box in the 15 can he brings the spout to the vertical position and then lowers the pump until the plate 9 is seated on the collar. At this time the oil box is lower than the partition 7 so that by rotating the pump one can bring 20 the thumb grip to its proper position above the handle and at the same time bring the end of the oil box having the suction valve therein towards the side of the can remote from the handle. The above being accomplished 25 one firmly fastens the pump in place by screwing down the cap 8.

When the can is to be used one grasps the handle and finger grip with the hand and places his thumb on the outer end of 30 the thumb grip. Then by alternately pressing down the thumb grip and releasing the same the oil is forcibly expelled through the spout. In the down-going movement of the plunger the oil previously drawn into 35 the oil box is forced upwardly into the spout past the check valve. In the up-going movement of the plunger under the action of the spring 26 oil is drawn inwardly through the suction valve to fill the box, which oil is subsequently expelled in 40 the down stroke of the plunger, the suction valve then closing and the check valve opening.

This device will discharge practically all 45 the oil from the can. The oil box is close to the bottom so that when the can is in the vertical position and the oil level is low the oil will be drawn into the box on the

up-stroke of the plunger. Should the can be tilted forwardly into the horizontal position or an inclined position between the horizontal and the vertical, there is oil trapped between the partition and the bottom of the can, which oil will be drawn into the pump on the suction stroke, even 55 although there is only a small quantity of oil in the can.

As the pump can be removed as a unit it is a very easy matter to inspect the same, as occasion requires.

What I claim as my invention is:

The combination with an oil container, said container being fitted with a handle and being provided at the top with a comparatively large opening and having the opening surrounded by a screw threaded up-standing flange, of a closure plate mounted on said flange and closing the opening, a cap screw threaded to the flange and fastening the plate in position, an oil delivery spout carried by the plate and extending downwardly towards the bottom of the can, an oil box passing transversely of the bottom of the container and opening to and carried by the lower end of the spout, a check valve in the spout, a suction valve carried by and opening to the interior of the box, a partition within the container and above the end of the box carrying the suction valve, a cylinder opening to and carried by the opposite end of the box, an upwardly spring pressed plunger within the cylinder, a plunger rod extending from the plunger and passing slidably through the closure plate and a thumb grip secured to the upper end of the rod, guided by the spout and having the outer end thereof positioned above and within convenient range of the handle.

Signed at Winnipeg, this 25th day of May, 1923.

EDWARD HAMEL.

In the presence of—

GERALD S. ROXBURGH,
M. B. KELLEHER.
